(57) **CLAIM**

The ornamental design for a head mounted display, as shown and described.

DESCRIPTION

FIG. 1 is a perspective view of a head mounted display showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the head mounted display and form no part of the claimed design. The dot-dash broken line defines the boundary of the claimed design and forms no part thereof.
